INFANT'S BOTTLEHOLDER OR SIMILAR
ARTICLE

Rudy Miller, Brooklyn, N. Y., assignor to Sirac,
Inc., Brooklyn, N. Y., a corporation of New York

Application February 1, 1950, Serial No. 7,617

Term of patent 14 years

(Cl. D83—8)

To all whom it may concern:

Be it known that I, Rudy Miller, a citizen of the United States, and a resident of Brooklyn, New York, have invented a new, original, and ornamental Design for an Infant's Bottle Holder or Similar Article, of which the following is a specification, reference being had to the accompanying drawing, forming a part hereof, in which

The bottle shown in dotted lines in Fig. 1 is for illustrative purposes only.

I claim:

The ornamental design for an infant's bottle holder or similar article, as shown and described.

RUDY MILLER.
